ARTHUR H. PITNEY, OF STAMFORD, CONNECTICUT, ASSIGNOR, BY MESNE ASSIGNMENTS, TO PITNEY-BOWES POSTAGE METER COMPANY, OF STAMFORD, CONNECTICUT, A CORPORATION OF DELAWARE.

POSTAGE-METER-REGISTER LOCKING AND RESETTING DEVICE.

Application filed March 3, 1924. Serial No. 397,869.

This invention relates to registering mechanisms used in the so-called "postage meter" machines of the type shown in my Patent #1,273,793, dated July 23, 1918; and more particularly to the machines shown in my Patent #1,370,668, dated March 8, 1921, and its Reissue #15,734 dated December 18, 1923. Such machines are designed for use by persons, firms, or corporations having a large number of letters or packages to mail, and enables them to buy any desired amount of prepaid postage from the Government, and thereafter print prepaid postage stamp indicia, from time to time, upon their mail matter, until the total amount of postage paid for is exhausted; whereupon the machine will become automatically locked so that no further stamps can be printed thereby until a further amount of postage is paid for and the meter reset by the proper official.

The present invention is an improvement on the registering mechanism shown in my application for patent on registering mechanism for postage meter machines, filed July 7, 1923, Serial No. 650,128.

The object of the present invention is to provide means for locking the printing die and registering mechanism of the meter, independently of the automatic means described in my aforesaid application whereby a meter, although still charged, may be rendered inoperative by a postal official.

I will explain the invention with reference to the accompanying drawings, which illustrate one practical embodiment of the invention; which, however, is capable of various changes within the scope of the invention; and it will be understood that the invention is adaptable to other meters or registering mechanisms in which are employed numeral wheels of the geared type. In the claims I have set forth the essentials of the invention and the novel features of construction and novel combinations of parts in which protection is desired.

In said drawings:

Figure 1 is a top plan view of a meter equipped with my improvements.

Figure 2 is a side view of the meter with part of the casing broken away to show interior mechanisms in elevation.

Figure 3 is a front end view of such meter.

Figure 4 is a detail section on the line 4—4, Figure 2.

Figure 5 is a partial side elevation, and partial longitudinal section through the base of the meter.

Figure 6 is a detail section on the line 6—6 of Figure 4.

Figure 7 is a detail section on the line 7—7, Figure 3.

Figure 8 is a bottom plan view of the meter looking upward, the base closing plate being removed.

The meter consists of a base casting 1 (Figures 1 and 2) provided with a printing die 2; an idler roller 3; and two registering mechanisms enclosed in a casing 9. The registering mechanisms are preferably of the geared type; and one of these registers (indicated at T, Figure 1) is called the "total" register, adds one unit to its count for every effective operation of the machine. This total register is never reset or "charged" and registers the total output of the meter. The other register (indicated at B, in Figure 1) is called the "balance register," and is arranged to subtract one unit for each effective operation of the machine from the number for which it was "set" or "charged"; and is automatically locked, or rendered inoperative, when it reaches "zero."

Suitable means are provided for operating the registering mechanisms in accordance with the effective operations of the die, this means being preferably such as shown and described in my aforesaid patents and applications, and therefore it is unnecessary to illustrate and describe the same in detail herein.

As shown, the total and balance registers are mounted in a frame comprising a base member 70, top plate 72, and side members 71 (Fig. 2). The balance register B comprises a series of similar numeral wheels 50 and a numeral wheel 60 of the highest denomination. The wheel 60 is located at the end of the series opposite the units wheel.

The shaft 52 of the balance register carries a spur gear 12 which meshes with a worm 11 on a vertical shaft 11^b journaled in the top plate 72 base, and the total register T may be also similarly geared to and operated from the shaft 11^b. These parts are preferably constructed and operated as

- described in my application filed July 12, 1922, Serial No. 574,427, and therefore need not be further described or illustrated in detail herein. The shaft 11^b may be driven by 5 the train of gears which drives the shaft 2^a of the die 2. This gearing may be substantially such as explained in my aforesaid patents and application, Serial No. 606,427, and needs no special description herein.
- 10 The ratio of the gearing bearing is such that for each revolution of the die the unit wheel of each of register B and T will make one-tenth of a revolution and alter the respective totals thereof one unit.
- 15 As described in my aforesaid application, Serial No. 650,128, a locking comb 68 is pivoted at 68^a beneath the registering mechanisms B and T (see Figs. 2 and 4), the teeth 68^b being in position to engage notches in 20 the numeral wheels of the balance register under pressure of the spring 68^c. When the notches in all the numeral wheels 50 are in alignment with the teeth 68^a, and the notches in the sleeve 66 and shell 60 are in alignment with tooth 68^{ax} (that is when all the 25 numeral wheels have returned to "0"), the locking plate 68 is moved in the position shown in dotted lines in Figure 4, and the balance register cannot be further operated 30 until the machine is reset, as fully described in the above mentioned application.
- As shown, a plate 68^b is attached to the bottom of locking comb 68, and a spring 68^c is attached to one end of the plate 68^b opposite the pivot 68^a. A part of plate 68^b is turned downwardly to form a catch member 68^e which is adapted to engage a catch member 6^c on the upturned end of a lever 6 which 35 controls the locking levers in the base of the meter. The opposite end of plate 68^b has a downwardly projecting lug 68^d adapted to be engaged by a push bar 76 to return the locking comb to its normal position and hold it therein while changing or resetting 40 the register B.
- The lever 6 practically corresponds in function to the lever 53 described in my application Serial No. 606,427, aforesaid, and the machine in which the register is used is 45 preferably provided with automatic devices whereby when the plate 68 is shifted to position to lock the numeral wheels of the balance register further operations of the machine are prevented. These devices, however, are fully described and claimed in my aforesaid patents and applications, and it is unnecessary to describe same in detail herein. When the locking comb engages all the 50 wheels of the balance register, the parts will become locked and no further effective operations can be made until said comb is disengaged from the numeral wheels of the balance register and reset in the position indicated in full lines in Figures 2 and 4.
- 60 In order to recharge the meter, it is necessary to restore both the trip lever 6 and the comb 68 to their original positions shown in full lines in Figures 4 and 5. This is accomplished by the following means:

As shown in Figures 2, 4 and 6, the catch 70 member 6^c projects into the path of a push bar 77, and the lug 68^d projects into the path of an oppositely movable push bar 76. These push bars are guided in aligned channels in the base plate 70 of the frame in which the 75 registering mechanisms and locking comb are mounted. The push bars 76 and 77 are in alignment, and are disposed at right angles to and on opposite sides of a slide bar 75 (see Figs. 4 and 6). Bar 75 is guided in 80 a channel in base 70, and lies at right angles to push bars 76 and 77, and bar 75 is provided with cam recesses 75^b and 75^c adjacent the inner ends of the push bars 76 and 77, these cam recesses being so disposed 85 that when the bar 75 is pulled outward said cams force bars 76 and 77 outward. When bar 75 is pushed inward the push bars 76 and 77 are moved inward by the action of a 90 spring 78 (Fig. 4) connected to the bars 76 and 77 and normally drawing them toward each other and holding their inner ends in contact with the bar 75.

When the push bars 76 and 77 are moved outward they respectively engage catch 95 member 6^c on trip lever 6 and the lug 68^d on the comb 68, and will force said parts from the positions shown in dotted lines in Fig. 4 to the positions shown in full lines therein. Pushing lug 68^d outward moves 100 the comb 68 downward, but as this cannot be done until the trip lever 6 is moved out from under the catch 68^e of the comb 68, the cam 75^b which moves the trip lever 6 is made to engage the cross bar 77, and carry 105 it to its farthest out position before the cam 75^c pushes bar 76 into engagement with lug 68^d thereby lowering the teeth 68^a from the slots in the numeral wheels, and dropping the lug 68^e into the path of catch 6^c, the said 110 lug 68^e (as shown in Fig. 2) being disposed to one side of the push bar 77. This insures a clear path for the catch 68^e in its downward course. A pin 75^d on the bar 75 moves in a slot 75^e and limits the travel of 115 bar 75 in both directions.

After the register has been properly reset the door 10 is closed. This door is provided with bosses 10^a and 10^b (Figs. 1 and 2) on its inner side, which will respectively engage the head 74 and the outer end of bar 75, and will prevent the door being closed if either bar 75 (or head 74) are not properly positioned after the register B has been reset or "charged."

A sheet metal guard plate 73 (Figs. 2, 6 and 7) is fastened inside the case 9, and is bent downwardly opposite the outer end of the registers (Fig. 2) and completely hides them. This plate is provided with slots in its top 130

opposite the sight openings, and in its front side has an aperture for the passage of knob 74, and a recess for the passage of bar 75 (Fig. 3). This plate prevents access to the register and tampering with the numeral wheels or mechanism when the meter is opened.

To charge or reset the register, unlock and open door 10 and pull bar 75 out to the stop. 10 Then pull slightly on knob 74 and turn it in the direction of arrow (Fig. 3) until the desired number appears at the sight opening for register B (Fig. 1). When numeral 1 shows (as in Fig. 1), the knob can be turned 15 no further, as the highest amount for which the register can be charged then appears at the sight opening. When the desired number appears knob 74 is released. Then bar 75 should be pushed back as far as it will 20 go, and the door 10 closed. This completes the resetting or charging operation.

The parts thus far described are or may be constructed substantially as more fully shown and described in my aforesaid application Serial No. 650,128.

In the present meters there is no way of clearing the meter,—that is, making the balance counter read "Zero," by turning the different numeral wheels back to 0. And if 30 the holder of a permit for using metered mail should for any reason desire to surrender his permit at a time when there yet remained a quantity of unused postage paid for in his meter, means must be provided for 35 preventing the meter (which is still charged with the unused balance) from the possibility of getting into the hands of an unscrupulous person who might attempt to unlawfully appropriate the unused postage by 40 inserting a new slug in the mortise in the die indicating a permit or license number different from that under which the meter is recorded in connection with the name of the user at the post office.

45 The present invention provides means to prevent such unlawful use and whereby the mechanisms of such meter can be placed in such condition that it can not be again used, no matter into whose possession it may come, 50 unless it is first released by the proper official. The novel devices about to be described will positively lock the meter and are only accessible by the proper post office official, authorized to charge and seal such 55 postage meters.

In my aforesaid application, Serial No. 650,128, the description of the locking devices was omitted on account of their similarity to my aforesaid application, Serial 60 No. 606,427, filed Dec. 12, 1922, and my application, filed March 14, 1923, Serial No. 624,997.

But to facilitate an understanding of the present invention, the locking levers and 65 driving gearing will be explained.

Referring to Figure 8, (the gears are indicated in dotted line to avoid confusion) a gear 100 is secured to the lower end of the shaft 2^a which drives the die and gear 100 drives the gear 11^a that operates the shaft 70 76 11^b driving the registering devices through an intermediate gear 101, which runs loosely on a stud 101^a. Gear 101 has secured to it a ratchet wheel 101^b and a cam 101^c, all rotating as if integral.

Fastened to gear 11^a is a stop disk 11^c similar to the stop disk 101^c.

A pawl 107 pivoted on a stud 107^a is held continually engaged with ratchet 101^b on gear 101, by a spring 107^s; and said pawl 107 will 80 prevent the train of gears being turned in a reversed direction.

A latch lever 102 is pivoted on a stud 102^a so that it can be oscillated to engage either a shoulder 101^d or stop disk 101^c, or a shoulder 11^d of stop disk 11^c; and when engaged with either disk it will lock the train of gears operated by and including the gear 100; but when latch lever 102 is in its normal intermediate position it engages neither of the 85 90 cams 11^c or 101^c and the train of gears can freely operate.

Latch lever 102 has an arm 102^b to which is connected one end of a link 104, and a spring 102^s, which control the position of 95 the latch lever 102 with relation to the two stop disks 11^c and 101^c.

A lever 103 pivoted on a stud 103^a has on its free end a head 103^d, whose face is machined concentric with the pivot stud 103^a, 100 and in said head 103^d is a socket 103^e which, when lever 103 is in its normal position, registers with a hole 1^h in the wall of the meter base 1. This hole 1^h and socket 103^e are provided for the entry of the meter pin 200 105 which is a part of the tripping mechanism of the postage meter machine to which the meter is attached, and with which it functions in the printing of metered mail indicia. When the socket 103^e is moved out of line 110 with hole 1^h, by the movement of lever 103, the meter pin cannot enter, and the meter cannot function. These parts operate as fully described in my Reissue Patent No. 15,734 dated December 18, 1923 aforesaid, 115 and therefore require no further detailed description here; pin 8 of said reissue patent corresponding with pin 200 of this application, and socket 54^a of said reissue patent corresponding with socket 103^e of this application; but it is necessary for pin 200 to enter the meter base 1 through hole 1^h, at every printing operation, and if for any reason its entry is prevented, no movement can be communicated to the die shaft in the meter, as explained in said patent.

The shutter lever 103 has an arm 103^b which is held in contact with the arm 102^b of the latch lever 102 by a spring 103^s. The 120 position of the arm 102^b and the pull of 130

spring 103^s control the position of lever 103 and determine whether socket 103^e shall be in or out of alignment with the hole 1^a.

The catch lever 6 is pivoted on a stud 6^a. One end of the lever is bent upward at 6^c (see Figs. 2, 4 and 6) and protrudes through a hole 1^b in the top of the meter base into position to be engaged by a lug 68^c on the locking comb 68 (as hereinbefore explained). The longer arm 6^b of said lever lies entirely within the base 1, and is connected by the link 104 to the arm 102^b of the latch lever 102.

The pull of spring 102^s is augmented by the pull of spring 103^s, and is communicated through link 104 to the lever 6 and tends to hold its upturned end 6^c in close contact with lug 68^c of the locking comb; and when said lug 68^c is lifted up out of engagement with 6^c by the upward movement of locking comb 68 at the discharge of the balance register (as has already been explained) the three levers 6, 102 and 103 will assume the positions indicated by dotted lines 6^{cz}, 102^z, 102^b, and 103^z, in Fig. 8. In such positions lever 102 engages stop disk 101^c and prevents the train of gears from turning; and the socket 103^e is out of alignment with hole 1^a, and prevents entry of meter pin 200; and this will prevent the die shaft being operated, as explained in my aforesaid reissue patent.

The foregoing explains the actions of the various parts and levers which render the meter inoperative when the balance register B reaches zero. But in order to lock the meter while the balance counter is still charged and the lever 6^c is still in engagement with latch 68^c, a different positioning of the levers must be effected, as the normal engagement of lug 6^c with lug 68^c, as shown in Fig. 4, would prevent the parts being positioned as just described.

As has been stated, the latch lever 102 will effectually lock the gear train whether it is in engagement with stop disk 11^c or stop disk 101^c; and it is also true that the meter pin 200 will be prevented from entering the socket 103^e, whether said socket be at the right or left of hole 1^a. In order to cause the levers 102 and 103 to take up the said latter positions (indicated by dotted lines 102^z and 103^z in Fig. 8) novel manually operable devices are introduced into the meter which can be operated without regard to the charged or discharged state of the balance register, said device, however, being so placed in the meter casing that they cannot be operated to lock the parts except by an authorized person having access to the interior of the meter.

As shown in Figs. 3, 6, 7 and 8, lever 6 has an arm 6^b extending almost at right angles thereto; and arm 6^b has a projecting lug 6^a which projects toward a small disk 105, which disk has projecting from its

lower face a pin 105^a. Said disk 105 has a shank 105^b, which projects through an opening in the top of base 1, into the space between the door 10 of the casing 9, and the guard plate 73, (Figs. 2, 6 and 7), adjacent the push bar 75. A sleeve 105^c is fastened to shank 105^b by screw 105^f, and prevents shank 105^b from moving longitudinally but permits it to be turned. A plate 105^d is fastened to sleeve 105^c and forms a convenient handle by which the shank 105^b and disk 105 can be turned. On account of the position of handle 105^d adjacent guard 73, the disk 105 can only be turned one half a revolution. The disk 105 can be held in one adjusted position by a detent 106 set in the base 70 of the counter frame and actuated by spring 106^s; and disk 105 can be held in its other adjusted position by a pin 75^p on the push bar 75 engaging handle 105^d (see Figs. 3 and 6).

The pin 105^a will occupy either the position shown in full lines in Fig. 8, or the position shown in dotted lines, Fig. 8, and the pin 105^a in passing from the position shown in full lines in Fig. 8 to the position shown in dotted lines, Fig. 8, will engage the end of lug 6^c and push it out of its path. This will cause end 6^c of lever 6, and 6^b to move to the positions indicated in dotted lines 6^{cz} and 6^{bz} in Fig. 8, which will move the upturned end 6^c of lever 6 out of contact with the latch lug 68^c and to the position indicated in dotted lines 6^{cz}, in Figs. 4 and 8, so that the position of lug 68^c will not then affect the lever 6.

The said movement of lever 6^b to position 6^{cz} also causes link 104 to move levers 102 and 103 to the position indicated in dotted lines 102^z and 103^z in Fig. 8, and thus locks the train of gears and prevents further operation of the meter or register.

A flange 1^a on the underside of the top of the base 1 (see Figs. 5, 7 and 8) will prevent any one improperly shifting the levers by inserting a thin piece of metal between the sliding plate 108 and the base 1.

With this invention, if it is desired to lock a meter out of service before the descending register is exhausted, it is only necessary to unlock and open the door 10; pull out the bar 75 by means of the cross pin 75^a; turn the handle 105^d over to the position shown in Fig. 3; then push back the bar 75; whereupon pin 75^p will hold handle 105^d securely. The bar 75 will then be held in such position when the door is closed; and when the door is locked and sealed the meter is safely locked against further use.

To put the meter into service again, so that the unused postage may be used, it is necessary for the proper official to open the door 10, pull out bar 75, turn handle 105^d, back to the position indicated in dotted lines in Fig. 3, and then lock and seal the door.

It is desirable when the meter is locked, either automatically or manually, as above described; to permit the die to be revolved a small fraction of a turn, to make it possible to change the slug in the die which prints the users' permit number on each piece of mail. Such limited turning can be permitted by having the pawl 107 which engages the ratchet wheel 101^b (Fig. 8) so placed as to allow the gears to be slightly turned back the necessary amount.

Operation.

When the numeral wheels of the balance register are locked at zero, to charge or reset the register, unlock and open the door 10, and pull the bar 75 out to the stop. By pulling the bar 75 outward the cam faces thereof force the push bars 76 and 77 outward thereby lowering the comb 68 so that the teeth 68^a, 68^{ax} thereof no longer engage the slots in the numeral wheels, and the comb 68 is held in down position. Then pull slightly on knob 74 turning same in the direction of the arrow (Fig. 3) until the desired number appears at the sight opening 9^s (Fig. 1). When the numeral 1 shows in the 6th place (Fig. 1) the knob can be turned no further. Knob 74 is then released, and the same springs back in place and the bar 75 should be pushed back as far as it will go and door 10 closed. The register is then reset.

Guard 73 prevents access to the register and tampering with the numeral wheels or mechanism when the meter is opened except bar 75 and knob 74 which extend through openings in the guard. While the meter is being reset the push bar 76 extended by the bar 75 engages the downwardly projecting lug 68^d and holds the comb 68 out of engagement with the slots in the numeral wheels so that the later may be reset by turning the knob 74.

Another downwardly projecting lug 68^e on the comb 68 engages catch member 6^c on the lever 6 which controls the locking levers in the base of the meter, catch member 6^c being normally yieldingly held into engagement with the lug 68^e by the action of the springs 102^s and 103^s acting on the arm 102 through link 104.

When however the numeral wheels register zero, and the teeth 68^a, 68^{ax} of comb 68 engage the slots in said wheels and comb 68 is thereby raised by action of spring 68^s, out of engagement with the catch 6^c of lever 6, the three levers 6, 102 and 103 will assume the positions indicated by dotted lines 6^{ex}, 102^x, and 103^x in Figs. 4 and 8, in which positions latch lever 102 engaging disk 101^c prevents rotation of the gear shaft 11^b and hence the numeral wheel shafts 52. Also socket 103^s being out of alignment with hole 1^b prevents pin 200 from entering therein, and the die shaft from rotating (as explained in my Reissue Patent #15,784), thereby rendering the meter inoperative when the balance register B reads "Zero".

In order to lock the meter while the balance counter is still charged and catch 6^c is still engaged with lug 68^e, the levers 102 and 103 must be thrown into the positions shown by dotted lines 102^x and 103^x in Fig. 8 by an authorized agent of the Post Office Department. This is done by opening the door 10 and manually throwing the lever 105^d thereby rotating disk 105 so that pin 105^a shifts the end 6^c of lever 6 into the position shown in dotted lines 6^{ex} in Figs. 4 and 8 so that the position of lug 68^e will not affect lever 6. In such position of lever 6, levers 102 and 103 are moved by link 4 to the position shown in dotted lines 102^x, 103^x in Fig. 8, and thereby lock the train of gears 85 and prevent further operation of the meter register.

I claim:

1. In a meter of the character specified, having a printer; a register; gearing between the printer and the register; and devices for directly locking the register; a latch lever adapted to lock the gearing; means for moving this latch lever in one direction; a second lever and connections whereby the latch lever is controlled by the second lever; and means whereby when the devices for directly locking the register are in unlocking position the latch lever is normally held disengaged said second lever being released when the said devices lock the register and the latch lever caused by said connection to lock the gearing to prevent further operation of the meter.

2. In a meter of the character specified, having a printer; a register; gearing between the printer and the register; and a locking comb for locking the register; a latch lever adapted to lock the gearing; means for moving this latch lever in one direction; a second lever and connections whereby the latch lever is controlled by the second lever; and an arm on the second lever having a lug adapted to be engaged by the locking comb when in unlocked position whereby the latch lever is normally held disengaged and when the locking comb locks the register said second lever is released and the latch lever caused to engage one of the gears of the train to prevent further operation of the meter.

3. In a meter of the character specified, having a printer; a register; a train of gearing between the printer and the register; and a locking comb adapted to engage and lock the register; a latch lever adapted to engage one or another of gears of the train to lock the gears; spring means for drawing the latch lever in one direction; a controlling lever adapted to be engaged by the locking

- comb when in unlocked position and whereby when the locking comb locks the register said controlling lever is released; and a link connecting the controlling lever with the 5 latch lever whereby the latch lever is controlled by the controlling lever and normally held disengaged when the locking comb is in unlocked position and when said locking comb is released the latch lever is caused to 10 engage one of the gears of the train to prevent further operation of the meter.
4. In a meter of the character specified, having a printer, a register, gearing between the printer and the register, and devices for 15 directly locking the register; a latch lever adapted to lock the gearing, and connections whereby when the devices for directly locking the register are in unlocking position the latch lever is normally held disengaged 20 and is released when the said devices lock the register; manually operable means whereby the meter can be manually locked before said mechanisms have automatically operated to lock the register.
5. In a meter of the character specified, having a printer, a register, gearing between the printer and the register, and devices for 25 directly locking the register; a latch lever adapted to lock the gearing, means for moving this latch lever in one direction, a second lever and connections whereby the latch lever is controlled by the second lever; manually operable means comprising a disk having a pin adapted to engage an arm of the 30 second lever and move said lever when the disk is manually turned, a sleeve attached to the shank of the disk, a handle on said sleeve, means for normally holding the disk in ineffective position, and means whereby 35 after the disk has been turned to shift the lever it will be held in such position when the casing is closed.
6. In a meter of the character specified, having an opening for the entry of a meter 40 pin, and containing a printer, a register, gearing between the printer and the register, and devices for directly locking the register; a latch lever adapted to lock the gearing, 45 means for moving this latch lever in one direction, and a second lever and connections whereby the latch lever is controlled by the second lever; and a third lever controlled by the latch lever adapted to prevent the entrance of the meter pin into the meter base when said latch lever is shifted to locking position.
7. In a meter of the character specified; a register, a train of gears driving the register, a lever adapted to engage either of adjacent gears to lock the same, means for holding this lever in unlocking position, 50 means controlled by the register locking mechanism adapted when the register locking mechanism is released to engage the lever with one of the gears, and manually operable means whereby the lever may be engaged with the other gear.
8. In a meter of the character specified a register, a train of gears for driving the register, a lever adapted to engage either of adjacent gears in the train to lock the same, a second lever, a link connecting said levers, a register locking device and connections adapted to hold the said second lever in position to keep the first lever in unlocked 55 position when the register is unlocked, and manually operable means for shifting the second lever to cause the first lever to lock the gear.
9. In a meter of the character specified, a register, a train of gears driving the register, a locking lever adapted to engage either of adjacent gears in the train to lock the same, a second lever, a link connecting said levers, a register locking device and 60 connections adapted to hold the said second lever in position to keep the first lever in unlocked position when the register is unlocked, means adapted to cause the locking lever to engage one gear when the register is locked by its locking device, and manually operable means for shifting the second lever to cause the first lever to lock the gear.

In testimony that I claim the foregoing as my own, I affix my signature.

ARTHUR H. PITNEY.
